UNITED STATES PATENT OFFICE.

SOTER B. TUSIS, OF CHICAGO, ILLINOIS.

HAIR-WAVING DEVICE.

1,377,943.

Specification of Letters Patent. Patented May 10, 1921.

Application filed February 16, 1920. Serial No. 359,147.

To all whom it may concern:

Be it known that I, SOTER B. TUSIS, a citizen of the United States, residing at Chicago, in the county of Cook and State 5 of Illinois, have invented new and useful Improvements in Hair-Waving Devices, of which the following is a specification.

This invention relates to a hair waving device and has for its primary object the 10 construction of a simple device capable of giving a perfect wave effect to the hair.

An object of the invention is the novel 15 manner of associating the parts so that this wave effect of the hair may be changed by changing the position and shape of various parts of my device.

Another object of the invention is the 20 construction of a device that will hold the hair in a "wave" shape while subjecting the hair to the action of electric currents.

A feature of my invention is the simple 25 construction of a device and the simple manner in which it may be connected to a strand of hair.

With these and other objects in view 30 the invention will be better understood from the following detailed description taken in connection with the accompanying drawing wherein—

Figure 1 is a perspective view of one form 35 of my invention.

Fig. 2 is a top plan view thereof.

Fig. 3 is a side elevation of another form 40 of my invention.

Fig. 4 is a top plan view thereof.

Fig. 5 is an end elevation of that form of 45 my invention shown in Fig. 3.

Fig. 6 is a top plan view of another form.

At the start I wish to call attention to 50 the fact that the device may have various other shapes and the parts associated in other relations than shown in the drawing as I am confident that the three forms illustrated will clearly convey the basic principle of my invention.

Again referring to the drawing illustrating 55 my invention but more particularly to Figs. 1 and 2 it will be noted that the device is constructed of a single piece of sheet material shaped to have a rectangular body portion 1 and a plurality of spaced cleats 2 projecting laterally from the body portion so that the strand of hair will be held

in place as clearly shown in Fig. 1. I wish 55 it to be understood that the cleats may be of a plurality of shapes and spaced apart equally or unequally depending upon the wave effect to be accomplished. The body portion 1 is provided with a wedge slot 3 in which the end of the strand of hair may 60 be forced to prevent accidental dislocation of the strand from the device.

In Figs. 3, 4 and 5 I have shown the cleats 5 of a different shape and construction. 65 Each cleat is of L shape form in cross section so that the edge 6 thereof will cause an abrupt curve in the strand of hair. This device will give a different wave effect than the device shown in Fig. 1. I wish it understood that the cleats 5 may be of any shape 70 and spaced apart at equal or unequal distances. It may be found advantageous in practice to curve the edge 6 as illustrated at 7 in Fig. 5 so as to automatically force 75 the individual hair toward the center of the cleat.

In Fig. 6 I have shown a device as having 80 a body portion 8 from which project staggered cylindrical cleats 9. If found advantageous in practice the rubber band 10 85 may be used to secure the end of the strand of hair.

In concluding my description I wish to lay stress upon the fact that the device may be of any suitable material such as metal, 85 celluloid, wood, or glass and the cleats may have any shape found advantageous and further these cleats may be spaced at equal or unequal distances apart depending upon the wave effect to be accomplished and 90 therefore I do not desire to be limited in any manner except as set forth in the claim hereunto appended.

Having thus described my invention what 95 I claim is—

As a new article of manufacture, a hair waving device formed of a flat piece of metal cut inwardly from one edge toward its longitudinal center to form tongues, 100 said tongues bent at right angles to the strip and the alternate tongues extending in the same direction from the strip and in the direction opposite to the tongues next thereto.

In testimony whereof I affix my signature. 105
SOTER B. TUSIS.
